EDMUND L. AHERN, OF BATTLE CREEK, MICHIGAN

PIPE THREADING MACHINE

Application filed December 4, 1930. Serial No. 500,067.

My invention relates to improvements in pipe threading machines, and it consists in the combinations, constructions, and arrangements herein described and claimed.

5 An object of my invention is to provide a pipe threading machine which is adapted for cutting a pipe in sections and threading the ends thereof.

10 A further object of my invention is to provide a pipe threading machine which is adapted for cutting a pipe and threading the ends of the cut sections thereof without removing either of the pipe sections from the machine.

15 A further object of my invention is to provide a pipe threading machine in which nipples may be threaded without the use of a nipple chuck.

20 A further object of my invention is to provide a pipe threading machine which will cut threads of various depths.

25 A further object of my invention is to provide a pipe threading machine in which a pipe may be cut into sections, the cut ends of said sections being threaded and reamed without removing the sections from the machine.

30 Other objects and advantages will appear in the following specification, and the novel features of the invention will be particularly pointed out in the appended claims.

35 My invention is illustrated in the accompanying drawings, forming part of this application, in which

40 Figure 1 is a front elevation of my device having parts thereof shown in section,

45 Figure 2 is a longitudinal sectional view of a portion of my device showing the dies and the structure by which they are actuated,

50 Figure 3 is a section taken along the line 3—3 of Figure 2,

55 Figure 4 is an end elevation of the housing shown in Figure 2 in which the pipe cutting structure is shown in elevation, the supporting table being shown in section,

60 Figure 5 is an end elevation of the structure shown in Figure 2 for regulating the depth of cut of the dies,

65 Figure 6 is an end elevation of the struc-

ture shown in Figure 1 showing the vise construction for holding the pipe,

70 Figure 7 is an elevation of a portion of the structure shown in Figure 4 for showing the reamer in attached position,

75 Figure 8 is a plan view of the reamer in attached position, and

80 Figure 9 is perspective detail view of portions of the device.

85 In carrying out my invention, I provide a 60 table or supporting member 1 which is substantially U-shaped in cross section and is provided with supporting portions 2 and 3. Supporting portion 3 is in the nature of a 90 housing. Gears are engaged in the housing 85 for the purpose hereinafter described. The supporting member 1 is provided with outwardly extending flanges or track portions 4. A pair of spaced-apart vise members 5 and 6 are disposed on the supporting member 1. Each of said vise members comprises a frame 7 having side portions 8 and 9 and a top portion 10. The side portions 8 and 9 are provided with recesses 11 for receiving the flange portions 4 whereby the vise frame 7 may ride on the flanges 4 and be restricted to a horizontal movement.

95 Longitudinally extending rails 12 are mounted on the inner side of the side portions of the supporting member 1 and are connected therewith in any desirable manner such as by bolts 13. The rails 12 are provided with rack teeth 14. A shaft 15 extends through the vise frame 7 and mounted thereon are gears 16 in mesh with the rack teeth 14 of the rails 12. The shaft 15 extends through the vise frame 7 and is provided with a manually actuated wheel 17 fixedly connected therewith whereby the gears 16 may be rotated. Thus it will be seen that 90 when the wheel 17 is rotated, the vise frame 7 will be moved along the supporting frame 1. The side 9 of the vise frame 7 is provided with an extending portion 18 to which is movably connected a locking member 19 95 having a handle 20. The locking member 19 is adapted for engaging a side of the supporting member 1 whereby the vise frame may be locked in position. The vise frame 7 is provided with a pair of gripping members 100

21 and 22 disposed one above the other and adapted for vertical movement toward or away from each other. A manually actuated wheel 23 is provided and is connected with the gripping members 21 and 22 by any means not shown since the same is old in the art whereby the gripping members 21 and 22 may be moved toward or away from each other. It will readily be seen that the gripping members 21 and 22 are adapted for receiving pipes of various diameters therebetween and it will be noted that regardless of the diameters of the pipes held between the gripping members 21 and 22, the center will remain constant. The cutter and die mechanism is disposed between the vise members 5 and 6 and comprises a carriage 24 having a base portion 25 and a superimposed portion 26 secured to the base portion 25 by any desirable means such as bolts 27.

The base portion 25 is provided with flange portions 28 having recesses 28' therein for receiving the flange portions 4 of the supporting frame 1. One of the flanges 28 is provided with rack teeth 29 on its lower side thereof. A gear wheel 30 is rotatably mounted on the exterior side of a side of the supporting frame 1 and meshes with the rack teeth 29. A manually actuated wheel 31 is fixedly connected with the gear wheel 30 whereby said gear wheel may be rotated for moving the carriage 24 longitudinally with respect to the supporting frame 1. The carriage 24 is provided with a cylindrical opening 32 therein in which is disposed a cylindrical casing or hollow cylinder 33 having an end 34 of reduced diameter. The cylindrical casing 33 is composed of two sections; namely, 35 and 36. Each side of the section 36 is provided with a tongue portion 37 receivable in a corresponding groove portion 38 of the section 35. The inner surface of the carriage 24 is provided with a circumferential recess 39. The casing 33 is provided with a circumferential flange 40 extending within the recess 39 and provided with peripheral teeth 41. A die stock 42 is disposed within the cylindrical casing 33 and is provided with projecting flanges 43 receivable in recesses 44 of the cylindrical casing 33 whereby the cylindrical casing 33 and the die stock 44 are locked together as a unit. The die stock 42 and the end 34 of the carriage 33 are respectively provided with cylindrical and aligned openings 45 and 46 extending therethrough, said openings being of sufficient size for receiving a pipe having a relatively large diameter. The die stock 42 is provided with radially extending openings 47 in which are disposed dies 48. The dies 48 are provided with slots 49 therein for receiving spring members 50 which are attached in any desirable manner to the die stock 42 whereby the dies may be held against displacement when the die stock 42 is rotated.

A stationary plate 51 is transversely positioned in a vertical plane with respect to the supporting member 1. The plate 51 is provided with side portions 52 which are secured to the sides of the member 1 on the inner sides thereof by any desirable means such as bolts 53. The plate 51 is provided with a relatively large circular opening 54 therethrough. A ring plate 55 is secured to the plate 51 by any desirable means such as bolts 56. The ring plate 55 is provided with a circular opening 57 therethrough of substantially the same diameter as the opening 54 in the plate 51 and in alignment therewith. The ring plate 55 is provided with a circular recess 58. A ring member 59 is rotatably disposed in the recess 58 and is held therein by the ring plate 55 and the plate 51. The die stock 42 is provided with a plurality of openings 60 therethrough, the number of openings 60 corresponding to the number of dies 48 and in radial alignment therewith, each of the dies 48 having a rounded end 48' extending within its respective opening 60. The ring member 59 is provided with a plurality of openings 61 therethrough equal in number to the openings 60 in the die stock 42 and in alignment therewith. Each pair of aligned openings 60 and 61 are provided with a pair of pin members 62 and 63 extending therethrough. The pin member 62 has one end fixedly connected with the ring member 59 by any desirable means such as bolts 64. The opposite end of the pin 62 may or may not be fixedly connected with the die stock 42. The pins 62 and 63 have beveled abutting faces 65 and 66, respectively. The abutting face of the pin 63 is provided with a tongue portion 67 as shown in Figure 9 receivable in a groove 68 in the face of the pin 62. A portion of the opposite face 69 of the pin 63 has oppositely beveled portions 70 and 71 meeting at the apex 72. The end portion of the pin 63 extending through the ring member 59 is provided with serrations 73 as shown at 73. The opposite end of the pin 63 is provided with a projecting portion 74.

A ring plate 75 is fixedly connected to the rotatable ring member 59 by any suitable means such as bolts 76'. The ring plate 75 is provided with a circumferential recess 76 for receiving an adjusting ring 77 provided with circumferential serrations 78 in mesh with the serrations 73 of the pins 63. The ring plate 75 and the ring member 59 are provided with a cylindrical opening 79 therethrough. It will be noted that the vise members 5 and 6, the casing 33 and the openings therethrough, the die stock 42 and the opening 45 therethrough, and the ring member 59, the ring plate 75, together with the cylindrical opening 79 extending therethrough, are in axial alignment. As shown in Figure 2, the die members 48 engage and ride on the beveled surfaces 71 of the pin members 63.

63. Spring members 80 are connected with the sides of the die stock 42 by any suitable means not shown and extend within the openings 60 engaging the faces 71 of the pins 63 on which they ride. A shaft 81 is disposed within the supporting member 1. The shaft has one end 82 slidably and rotatably mounted in a bearing member 83 connected with the supporting member and the other end 84 rotatably mounted in a projecting portion 85 of the carriage 24. A gear 86 is fixedly mounted on the shaft 81 and extends through an opening 87 shown in dotted line position in Figure 3. The gear 86 is in mesh with the teeth 41 of the casing 33 whereby said casing may be rotated within the carriage 24.

Since the die stock 42 is fixedly mounted within the casing 33, the casing 33, the die stock 42 and the dies 48 carried thereby, together with the pins 62 and 63, the ring member 59, the ring plate 75 and the adjusting ring 77, will be rotated as a unit by the gear 86.

25 A pair of housings 88 and 89 are mounted on the exterior of the end 34 of the casing 33 by any suitable means such as bolts 90. The housings 88 and 89 are oppositely positioned with respect to the opening 46. The housing 88 is provided with a forked bearing member 91 which extends without the housing and is adapted for being moved radially with respect to the casing 33 by means of a manually actuated wheel 92. The housing 82 is provided with a cutting member 93 which is likewise mounted in the housing 89 and is also adapted for being moved radially with respect to the casing 33 by means of a wheel 94. The construction of the 35 housings 88 and 89 and their associated mechanisms is not shown since the same is old in the art and other types of such mechanisms might be utilized without departing from the spirit of my invention.

40 As shown in Figure 4 the end 34 of the section 36 which, together with the section 35, comprises the casing 33 is provided with lug portions 95 receivable in recesses 96 of the section 35. Diametrically opposed projecting members 97 are connected with the end 34 of the section 36 on opposite sides of the opening 46 for a purpose hereinafter described. As shown in Figure 1 a gear 98 is rigidly mounted thereon and is in mesh with a gear 99 mounted on a shaft 100 which in turn is rotatably mounted in the supporting portion 3 of the supporting member 1. The gear 99 is connected by a train of gears to a motor 101. The gears disposed in the housing support 3 function as a transmission and may be shifted by any desirable means not shown for varying the speed ratio of the gear 98 with respect to the motor shaft 102.

45 From the foregoing let us assume that it is desired that a piece of pipe be cut at any

intermediate points and that the cut end portions be threaded. A pipe 103 shown in dotted line position in Figure 1 is inserted through the opening 46, the stock opening 45, and the opening 79. By moving the handles 20 upwardly and rotating the wheels 17, the vises 5 and 6 may be moved on the supporting table 1 until they are in the proper position for supporting the pipe. The wheels 23 of the vises are then rotated until the gripping members 21 and 22 engage and hold the pipe. Before the pipe is put in the machine it is first marked where it is desired to be cut. When the pipe is put in the vises, the mark is positioned in the vicinity of the cutter 93. When the pipe has been locked in the gripping members 21 and 22, the wheel 17 of the vise 5 may then be rotated for bringing the mark on the pipe in the path of the cutter 93, at which time the handles 20 of the locking members on both the vises 5 and 6 are moved downwardly for locking the vises in position. The bearing member 91 is then moved in engagement with the pipe so that the pipe will not buckle while being cut. The gears in the housing support 3 are then shifted by any means not shown for rotating the shaft 81 at the proper speed whereby the casing 33 may be rotated by 50 which means the cutter 93 rotates about the pipe for cutting the same. After the pipe has been cut, the shaft 81 is then stopped from rotating and the cutter 93 and the bearing member 91 are moved away from the pipe. The locking members 19 of both vises 5 and 6 are then moved out of engagement with the supporting member 1. The wheel 17 of the vise 5 is then rotated in a counterclockwise direction when viewed as 55 in Figure 1 whereby the pipe is moved through the casing 33 and the carriage 36 until the cut in the pipe is substantially in line with the apices of the pin members 63. The vises 5 and 6 are again locked to the supporting member.

60 The shaft 81 is again set in motion for rotating the casing 33. The wheel 31 shown in Figure 1 is then rotated in a counterclockwise direction for moving the carriage 24 in the direction of the arrow 105 at which time the die stock 42 as shown in Figure 2 moves along the pins 62 and 63. As the die stock moves along the pins 62 and 63, the dies 48, by reason of their travelling along the beveled surfaces 71 of the pin 63, are moved inwardly for threading the pipe and continue moving inwardly as the die stock 42 travels along the pins in the direction of the arrow 105 until the dies 48 reach the apices 72 of the pins 63, at which time they have 65 reached the peak of their inward movement which is at the point where the pipe is cut. As the die stock continues its movement, the dies 48 move outwardly with respect to the pipe by reason of the receding bevels 70 of the 70 pipe.

pins 63. Until the dies move out of engagement with the pipe, the rotation of the shaft 81 is stopped. The springs 50 connected with the stock 42 and receivable in the recesses 49 of the dies serve to hold the dies 48 in positive engagement with the beveled surfaces 70 and 71 of the pins 63. The springs 80 connected with the stock member 42 and riding on the beveled surfaces of the pins 63 are provided for keeping the beveled surfaces free from the cuttings so that the dies will not ride over the cuttings and thereby make an irregular cut. It will readily be seen that it is only necessary that the wheel 31 be rotated for moving the carriage 26 until the dies engage with the pipe as the dies in cutting the pipe will carry the carriage along until they have completed the threading of the pipe and move out of engagement therewith.

After the pipes have been threaded and the shaft 81 has ceased rotating, the vise lock 19 is then moved out of engagement with the supporting member 1 and the vises moved away from each other so that the ends of the pipe cannot come in contact with the dies regardless of the position of the carriage 26. The cutting and threading of a pipe leaves a bur on the end thereof which is not desirable. To cut away this bur I provide a double faced reamer 106 comprising a plate 107 having openings therein for receiving the threaded projections 97, said plate being held on said projections by means of nuts 108. A conical reamer 109 is mounted on each side of the plate 107 and in actual alignment with the pipe sections. One of the reamers 109 extends through the opening 46 and into the casing 33. It will readily be seen that the pipe section extending through the opening 46 must be withdrawn after the threading process before the reamer can be attached. After the reamer is attached to the casing 33 the shaft 81 is again set in rotation for rotating the casing 33 and the pipe sections are moved toward the rotating reamer by means of the wheels 17 of the vises 5 and 6 until the ends of the pipes engage the reamer whereby the burs are cut away. After the burs have been removed the pipe sections are then removed from the vises. It will readily be seen that the reamer must be removed before another pipe can be inserted in the device for being cut and threaded.

The device is also adapted for making nipples without a nipple chuck in the following manner: The end of a section of pipe is marked for the length of a nipple which it is desired to make. The section of pipe is then disposed in the vise 5 in the manner hereinbefore described and extends through the casing 33, the end thereof being in substantial alignment with the apices 72. The end is then threaded, assuming of course that it has not previously been threaded. The pipe is

then moved away from the die stock 42 so that it will not engage with the dies 48 and the die stock 42 is moved back to the position shown in Figure 2. If it has been threaded, then this operation is unnecessary. The pipe is then moved through the die stock until the marked portion is in alignment with the apices 72 and the dies are then set in motion for carrying out the whole threading operation as hereinbefore set forth. The pipe is then withdrawn from the die stock 42 until the deepest threaded cut, which would be at the marked portion, is in line with the cutter 93, at which time the cutter and the casing 33 are actuated for cutting the threaded nipple from the pipe. It will be seen by referring to Figure 2 that by rotating the adjusting ring 77 by means of an instrument inserted in one or more of the openings 110 the pins 63 will be moved with respect to the pins 62 for varying the depth of cut of the die members.

I claim:

1. A device of the type described comprising a supporting table, a pair of spaced-apart vise members movably mounted on said table, means for locking the vises to the table, said vises being adapted for gripping a pipe, a carriage disposed between the vise members and in alignment therewith, said carriage being movably mounted on the table and adapted for permitting the pipe to extend therethrough, a casing rotatably mounted within the carriage, means connected with the casing whereby said pipe may be cut at an intermediate point thereof, means whereby said carriage may be moved horizontally and said casing rotated therein simultaneously, a die stock fixedly mounted within said casing and rotatable therewith, die members carried by said die stock, said die members being adapted for providing the abutting ends of the cut pipe sections with tapered threaded end portions when said carriage is moved simultaneously with the rotation of the casing, means for varying the depth of cut of the die members, said means comprising a plurality of beveled elements extending through said die stock and rotatable therewith, said beveled elements being movable longitudinally with respect to the die stock, said dies being in engagement with the beveled elements and radially movable with respect to the axis of rotation depending on the direction of movement of the beveled elements, and means for adjustably positioning the beveled elements.

2. A device of the type described comprising a supporting frame, a pair of vise members movably mounted on the supporting frame and disposed in spaced-apart positions, said vise members being adapted for gripping a cylindrical member, a housing movably mounted on the supporting frame and positioned between the vise members, a drum rotatably mounted in the housing, a cutting ele-

ment mounted on the drum and adapted for cutting the cylindrical member for providing a pair of cylindrical sections, said vise members being adapted for supporting the sections, and die members mounted in the drum for threading the adjacent ends of the sections when the drum is rotated.

3. A device of the type described comprising a supporting frame, a pair of vise members movably mounted on the supporting frame and disposed in spaced-apart positions, means for holding the vise members in locking engagement with the supporting frame, said vise members being adapted for gripping a cylindrical member, a housing movably mounted on the supporting frame and positioned between the vise members, a drum rotatably mounted in the housing, a cutting element mounted on the drum and adapted for cutting the cylindrical member for providing a pair of cylindrical sections, said vise members being adapted for supporting the sections, a die stock mounted in said drum, and die members mounted in the die stock for threading the adjacent ends of the section when the drum is rotated.

4. A device of the type described comprising a supporting frame, a pair of vise members movably mounted on the supporting frame and disposed in spaced-apart positions, means for holding the vise members in locking engagement with the supporting frame, said vise members being adapted for gripping a cylindrical member, a housing movably mounted on the supporting frame and positioned between the vise members, a drum rotatably mounted in the housing, a cutting element mounted on the drum and adapted for cutting the cylindrical member for providing a pair of cylindrical sections, a die stock mounted in said drum, and die members mounted in the die stock and radially movable with respect thereto, said die members being adapted for providing the cylindrical sections with tapered threaded end portions when the drum is rotated.

5. A device of the type described comprising a supporting frame, a pair of vise members movably mounted on the supporting frame and disposed in spaced-apart positions, said vise members being adapted for gripping a cylindrical member, a housing movably mounted on the supporting frame and positioned between the vise members, a drum rotatably mounted in the housing, a cutting element mounted on the drum and adapted for cutting a cylindrical member for providing a pair of cylindrical sections, said vise members being adapted for supporting said sections, a die stock mounted on the drum and provided with longitudinal openings therethrough, bar members disposed in said openings and provided with beveled faces, said die stock being slidable with respect to the bar members, and die members mounted in

the die stock and radially movable with respect thereto, said die members being in engagement with the bar members for providing the cylindrical sections with tapered threaded end portions when the drum is rotated.

6. A device of the type described comprising a supporting frame, a pair of vise members movably mounted on the supporting frame and disposed in spaced-apart positions, said vise members being adapted for gripping a cylindrical member, a housing movably mounted on the supporting frame and positioned between the vise members, a drum rotatably mounted on the housing, a cutting element mounted on the drum and adapted for cutting a cylindrical member for providing a pair of cylindrical sections, said vise members being adapted for supporting said sections, a die stock mounted on the drum and provided with longitudinal openings therethrough, bar members disposed in said openings and provided with beveled faces, said die stock being slidable with respect to the bar members, die members mounted in the die stock and radially movable with respect thereto, said die members being in engagement with the bar members for providing the cylindrical sections with tapered threaded end portions when the drum is rotated, and means for changing the radial position of the bar members with respect to the die stock for varying the depth of the cut of said die members.

7. A device of the type described comprising a supporting frame, a pair of vise members movably mounted on the supporting frame and disposed in spaced-apart positions, said vise members being adapted for gripping a cylindrical member, a housing movably mounted on the supporting frame and positioned between the vise members, a drum rotatably mounted on the housing, a cutting element mounted on the drum and adapted for cutting a cylindrical member for providing a pair of cylindrical sections, said vise members being adapted for supporting said sections, a die stock mounted in the drum and provided with an axial opening therethrough for receiving a cylindrical member, said die stock being further provided with radially positioned spaced-apart longitudinal passageways therethrough, bar members rotatably mounted on the supporting frame and extending through said passageways, said bar members being rotatable with, and slidable with respect to, said die stock, and die members movably mounted in the die stock and in engagement with the bar members, said bar members being provided with oppositely beveled faces for varying the radial positions of said die members when the die stock is moved with respect to the bar members.
